UNITED STATES PATENT OFFICE.

STEPHEN CELINSKI, OF BUFFALO, NEW YORK.

DESIGN FOR A LENS FOR AN AUTOMOBILE HEADLIGHT.

Application filed February 11, 1922. Serial No. 650. Term of patent 14 years.

To all whom it may concern:

Be it known that I, STEPHEN CELINSKI, a citizen of the United States, residing at Buffalo, in the county of Erie and State of New York, have invented a new, original, and ornamental Design for a Lens for an Automobile Headlight, of which the following is a specification, reference being had therein to the accompanying drawings.

Figure 1 is a plan view of a lens for an

automobile headlight, showing my new design.

Figure 2 is a cross section of Fig. 1, taken on line 2—2.

I claim:

The ornamental design for a lens for an automobile headlight, as shown.

In testimony whereof I hereunto affix my signature.

STEPHEN CELINSKI.
